AUTOMATIC PROMPTER ATTACHMENT FOR TYPEWRITERS

Ernest J. Fentos, New York, N. Y.

Application November 6, 1953, Serial No. 390,611

1 Claim. (Cl. 120—32)

This invention relates to new and useful improvements in copyholders for typewriters.

More particularly, the present invention proposes the construction of an improved copyholder or "prompter" which will hold a roll of copy, such as a mailing list, adjacent the platen of a typewriter in ready view with only a portion of the roll and copy thereon visible, and which will change such portion of the roll and copy as the platen is moved.

Another object of the present invention proposes forming the copyholder or "prompter" with a clutch device so that the platen can be moved without moving the copy roll when such is desired.

Still further, the present invention proposes constructing the copyholder so that it can be readily removed from a typewriter or permanently attached to it.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a typewriter equipped with a copyholder or "prompter" constructed and arranged in accordance with the present invention.

Fig. 2 is a sectional view taken on line 2—2 of Fig. 1.

Fig. 3 is a sectional view taken on line 3—3 of Fig. 1.

Fig. 4 is a sectional view taken on line 4—4 of Fig. 3.

Fig. 5 is a view similar to Fig. 4 but showing the clutch key retracted.

Fig. 6 is an end view illustrating a modification of the present invention.

Fig. 7 is a fragmentary front view similar to Fig. 1 but illustrating another modification of the present invention.

Fig. 8 is a fragmentary sectional view taken on line 8—8 of Fig. 7.

Fig. 9 is an enlarged fragmentary sectional view taken on line 9—9 of Fig. 7.

Fig. 10 is a fragmentary perspective view of a belt similar to the upper belt shown in Fig. 7 but illustrating another modification of the invention.

The copyholder or "prompter," in accordance with the first form of the invention illustrated in Figs. 1 to 5, inclusive, has a frame 15 in box form.

Frame 15 has a top 16, bottom 17, back 18 and two opposed roll supporting sides 19 and 20. A front opening or window 21 is provided in the front 22 of the frame 15. Side 19 of the frame is attached to the bottom 17 by a hinge 23 and a lock 24 removably secures the side 19 to the top 16 of the frame (see Fig. 3). In this manner, the side 19 may be pivoted on its hinge 23 to permit access to the interior of the frame.

Clamps 25 and 26 fixed to frame 15 provide means removably and slidably to attach the frame 15 to a typewriter 27 adjacent one end of the platen 28 as will

later be more fully described. It is obvious, however, that if desired the clamps may be permanently attached to the typewriter.

An axle 29 is rotatably mounted in the two opposed roll supporting sides 19 and 20 of the frame 15, the axle 29 extending between the sides 19 and 20. One end 30 of axle 29 is journaled in side 19 and the other end 31 is journaled in and extends through side 20, for disposal adjacent the platen 28 of the typewriter. A gear engaging portion 32 is formed on the end 31 of axle 29.

Mounted on the end of platen 28 of typewriter 27 is a gear 33. The platen shaft 34 is fixed to a stub shaft 35 and gear 33 is freely mounted on the free turned down end of the stub shaft 35. A retainer ring 36 (see Figs. 4 and 5) holds the gear on the stub shaft 35. The stub shaft 35 may be an integral portion of the platen shaft 34 or it may be secured to the platen knob 34a by a suction cup or slip clutch 34b, or by a suitable clamping band around the platen knob 34a.

A take-up roll 37 is similarly mounted in the frame 15 spaced from the axle 29. One end 38 of the roll 37 is journaled in side 19 of the frame 15 and the other end 39 of the take-up roll 37 is journaled in and extends through the side 20 of the frame. A gear engaging portion 40 is provided on end 39 of the take-up roll 37.

The gear engaging portions 32 and 40 of the axle 29 and take-up roll 37, respectively, are operatively engaged with the gear 33 being disposed on opposite sides of the gear. In this manner, the axle 29 and take-up roll 37 are rotated by the gear 33.

Gear 33 and stub shaft 35 have alignable keyways 41 and 42 and a key 43 slidably fits these keyways 41 and 42 for removably fixing the gear to the stub shaft. Fig. 4 illustrates the key position when the gear 33 is fixed to the stub shaft 35 and Fig. 4 shows the retracted position of the key 43. In this manner, a clutch is provided which when engaged (see Fig. 4) connects the axle 29 and take-up roll 37 directly with the platen 28 of the typewriter and when disengaged (see Fig. 5) permits the platen 28 to be turned without rotating the axle 29 or take-up roll 37.

Gear 33 is rotatably held between the gear engaging portions 32 and 40 of the axle 29 and take-up roll 37 by retainer rings 29a and 37a respectively which are positioned on opposite sides of the gear 33. The frame 15 is slidably mounted on clamps 25 and 26 by brackets 18a extending from the back 18 of the frame and slidably encircling arms 25a and 26a of the clamps 25 and 26 respectively. In this manner, the frame 15 is free to move with the platen 28 of the typewriter 27 being connected with it.

To operate the device, a roll 44 of copy material such as a mailing list having names and addresses spaced according to the spacing of the typewriter 27 is mounted on the axle 29, the side 19 of the frame 15 being lowered or opened to permit this, and secured to the take-up roll 37 in the manner that a roll of film is placed in a camera. When the clutch is engaged, that is when the key 43 fixes the gear 33 to its stub shaft 35, movement of the platen 28 of typewriter 27, as by using the lever 45, moves the copy roll 44. By proper spacing of the names and addresses on the copy roll 44, only that portion of the copy roll 44 which contains the name and address to be typed will appear in the window 21 of the frame 15. This will prompt the typist to type only the proper name and address. When the typist moves the platen 28 in the normal spacing operation while typing, this will move the copy so that when the paper in the typewriter is ready for typing the next name and address, that name and address will appear on the prompter.

The modification of the present invention illustrated

in Fig. 6 is characterized by the provision of a different clutch 45. The roll holding axle 29' and take-up roll 37' are loosely journaled in and extend through side 20' of frame 15'. Rocker arms 46 and 47 are connected at one end to the ends of axle 29' and take-up roll 37', respectively, which extend through side 20' of frame 15'. Straps 48 and 49 are fixed to the frame 15' and the rocker arms 46 and 47 are pivotally connected respectively with these straps by pivot pins 50. Springs 51 and 52 also connect the rocker arms 46 and 47 with the straps 48 and 49 to bias them into the position shown in solid lines in Fig. 6 wherein the gear engaging portions 32' and 40' of the axle 29' and take-up roll 37' are engaged with the gear 33' fixed to the platen axle 53.

15 Rocker arms 46 and 47 have handle portions 54 and 55, respectively, to rock them into the position indicated in broken line outline in Fig. 6 wherein the axle 29' and take-up roll 37' are disengaged from the gear 33.

The modification of the present invention illustrated in Fig. 7 is characterized by the provision of a frame 56 having opposed sides 57 and 58 secured to magnet 59 for removably attaching the frame to a typewriter 60 below one end of the platen 61 and platen shaft 62.

20 A roller shaft 63 having spaced lengthwise ridges 64 is rotatably mounted on the frame, one end being journaled in the side 57 of the frame and the other end journaled in side 58. A belt 65 having spaced transverse grooves 66 extends between the roller shaft 63 and platen shaft 62 and connects the two for rotation of the roller shaft by and with the platen 61.

25 A sleeve 67 having ridges or teeth 68 is rotatably mounted on the platen shaft 62 and the upper end of belt 65 fits over this sleeve. The sleeve 67 and the platen shaft 62 have aligning keyways 69 and 70 respectively and a key 71 slidably fits in the keyways to fix the sleeve 67 and platen shaft 62 together and to permit relative movement between them when desired. In this manner, the platen can be moved when desired without moving the roller shaft 63.

30 An axle 72, spaced from the roller shaft 63, is mounted on the frame 56 between the sides 57 and 58 removably to receive and hold a roll of copy material 73. A take-up roll 74 constructed similar to roller shaft 63 is spaced from the axle 72 and rotatably mounted on the frame 56, the ends of the take-up roll being journaled in sides 57 and 58 of the frame. The take-up roll is adapted for winding the copy material from the axle 72 onto the take-up roll. A belt 75 between the take-up roll and the roller shaft 63 connects the two for rotation of the take-up shaft by the roller shaft. Belt 75 is constructed

35 similar to belt 65. In Fig. 10, a belt 76 is shown which can be used for belts 65 and 75. The belt 76 has two ends 77 and 78 which may removably be joined together by hooks 79 and eyes 80.

40 While I have illustrated and described the preferred embodiments of my invention, it is to be understood that I do not limit myself to the precise constructions herein disclosed and the right is reserved to all changes and modifications coming within the scope of the invention as defined in the appended claim.

Having thus described my invention, what I claim as new, and desire to secure by United States Letters Patent is:

A typewriter copyholder comprising a frame having two opposed roll supporting sides and a clamp to attach the frame to a typewriter adjacent one end of the platen, an axle rotatably mounted in said two opposed roll supporting sides of the frame to hold a roll of copy material, said axle having one end extending through one of said sides and disposed adjacent the platen, said end of the axle having a gear engaging portion thereon, a gear mounted on the end of the platen adjacent said axle and engaged with the gear engaging portion thereof for rotating the axle with and by the platen, a take-up roll spaced from the axle and rotatably mounted in said two opposed roll supporting sides of the frame, said take-up roll having one end extending through the same side of the frame as the axle and having a similar gear engaging portion thereon operatively engaged with the gear to rotate the take-up roll by and with the platen, a clutch to disconnect the platen and the axle and take-up roll, said clutch being a key, a stub shaft fixed to the platen, said gear being freely mounted on the stub shaft, said stub shaft and said gear having alignable keyways, and a key for removably fixing the gear to the stub shaft.
